Garrison Smith, Henry Brown & Sam'l H. Sailor, of Philadelphia, Pa.

Assignors to

J. G. Abbott, and A. Lawrence, of Philadelphia, aforesaid.

Letters Patent No. 942, Dated Sept. 8th 1857.

The schedule referred to in the Letters Patent, and making part of the same.

To all whom it may concern:

Be it known that we, Garrison Smith, Henry Brown, & Sam'l H. Sailor, of the City and County of Philadelphia, and State of Pennsylvania, have produced a new and original design for Stove base, top, and door, and we, do hereby declare that the following is a full, clear and exact description of the same; reference being had to the annexed drawing, forming part of this specification, in which

Figure 1, is an elevation of Base and Top.

Figure 2, is an elevation of door and frame.

Figure 3, is a top view of base plate.

Figure 4, is a view of open plate P, designed to be placed upon front of the stove cylinder.

Figure 5, is a view of foot.

Similar characters of reference in the several figures denote the same part of stove and design.

The base plate B, has the form shown in the drawing,

and is ornamented in bas-relief, by centerpiece a, foliage b, scrolls c, and flowers d and e, along its front edge; the arrangement and configuration being as shown in the drawing, this plate bears the inscription "Abbott & Lawrence, Patented 1857, Philadelphia" in raised capitals and numerals.

The vertical portion v, of the base is ornamented with figures f, g, h, in bas-relief, having the configuration and arrangement set forth in figure 1. Above this portion of the base is an overhanging wavy edge u, ornamented as shown in the drawing.

The fixed portion of the top t, is made up of curved surfaces i, and mouldings j; and has an overhanging edge made up of figures k, k', m, with openings m and o, between them. The movable portion of the top, designated by the letter A, is of elliptical form, rising towards the center, where an ornamental handle q, is attached. The curved surface of this plate is ornamented in bas-relief as shown in the drawing.

The foot F, is ornamented with scrolls p and foliage n, arranged and having the configuration shown in fig. 5.

The frame D, of the feed door is ornamented with foliage t, and flowers u, and the vertical cross bar of the door is connected at middle with the sides, by foliage a; the form of door and frame and the ornaments thereof, being as set forth in figure 2.

The open plate P, is made up of sweeping foliage f', g', h', and i', arranged and having the configuration shown in figure 4.

What we claim as new and of our own production, and desire to secure by Letters Patent, is

The ornamental design of the several castings before stated as herein described and delineated in the accompanying drawing, forming a design for a stove.

In testimony whereof, we have hereunto signed our names before two subscribing witnesses.
